UNITED STATES PATENT OFFICE.

ELMER EDMOND NIDA, OF MILLFIELD, OHIO.

COAL-CAGER.

1,355,414.

Specification of Letters Patent. Patented Oct. 12, 1920.

Application filed July 6, 1920. Serial No. 394,025.

To all whom it may concern:

Be it known that I, ELMER E. NIDA, a citizen of the United States, residing at Millfield, in the county of Athens and State of Ohio, have invented a new and useful Coal-Cager, of which the following is a specification.

This invention relates to caging apparatus for use at the bottom of a mine shaft, one of the objects of the invention being to provide automatic means whereby, when a cage is brought to position to receive a car, it will automatically operate mechanism for releasing one car of a trip while the remaining car or cars will be held until the cage has moved away whereupon the next car of the trip will be brought automatically to position to be delivered to the cage when the cage is again returned for a load.

Another object is to provide mechanism of this character which is simple, durable and efficient and can be applied readily.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a plan view of the apparatus, a portion of the shaft being shown.

Fig. 2 is a section on line 2—2, Fig. 1.

Fig. 3 is a detail view of one of the horns.

Referring to the figures by characters of reference 1 designates stringers on which are secured the rails 2 leading to the shaft 3 of the cage, there being a cross beam 4 to which the stringers 1 are secured and which constitutes a portion of one wall of the shaft. The rails 2 are not mounted directly on the stringers 1 but are fastened to cross ties 5 interposed between the stringers and the rails.

Secured to the ends of one of the ties 5 at points beyond the sides of the track are brackets 6 to each of which is pivotally connected a bell crank lever 7 one arm of which is curved upwardly to form a horn 8 while the other arm extends inwardly under the rails 2. The horn 8 may be pro-

vided with a reinforcing strip 9 extending downwardly from the point thereof and adapted, when the horn is in wheel engaging position, to rest upon the top of the rail as shown in Figs. 1 and 2.

Secured to each of the inwardly extending arms of the bell crank lever 7 are links 10 the forward ends of which are preferably forced, as shown at 11, and are connected by a pivot pin 12 to upwardly extending arms 13 of an angular trip 14. The angle portion of this trip is pivotally connected to brackets 15 by a cross pin or bolt 16 and a roller 17 is carried by the free end 70 of the strip and is supported in the shaft 3 and in the path of the cage.

Secured to the sides of the rails 2 or to any other suitable structure are brackets 18 to each of which is pivotally connected the angle portion of a bell crank lever 19, one arm of each lever extending under the adjacent rails 2 while the other arm is curved upwardly to form a horn 20. The inwardly extending arm of each bell crank lever is 80 pivotally and slidably connected, as at 21, to one arm of a lever 22 fulcrumed between the rails. The other arms of the two levers 22 are connected by links 23 to the inner ends of the bell crank levers 7. Links 24 85 connect the rods 23 to a cross head 25 which, in turn, is connected by a spring 26 to a cross bar 27 attached to the rails.

It will be apparent that the spring 26 serves to hold the horns 20 normally swung 90 laterally away from the rails and also, by pulling through the rods 23 upon the bell crank levers 7, serves to hold the horns 8 normally pressed against the sides of the rails 2, and the free end of the trip 14 normally elevated as shown in Fig. 2. The horns 8 and 20 are so positioned relative to each other that when the front wheels of the first car of the trip are in engagement with the horns 8, the rear wheels of the first 100 car of the trip will be in advance of the horns 20 while the front wheels of the second car of the trip will be in position just back of the horns 20. Thus it will be seen that when a trip of cars gravitates toward the shaft 3 the front wheels of the first car will come against the horns 8 so as to stop the movement of the trip of cars. When a cage descends in the shaft 3 and comes against the trip 14 said trip will be lowered 110 and the arms 13 will pull through the rods 10 upon the bell crank levers 7 so as to

swing the horns 8 laterally out of engagement with the wheels of the first car. At the same time the rods 23 will pull on the levers 22 and swing the horns 20 inwardly 5 so as to engage the front wheels of the second car. As soon as the front car is released it will gravitate onto the cage and when the cage moves upwardly, thus releasing the trip 14, the spring 26 will automatically swing the horns 20 laterally out of engagement with the car wheels and move the horns 8 back to the position shown in Fig. 1 so that the trip of cars will move forwardly and the first car of the trip will 15 come against the horns 8. Thus the cars will be reset awaiting the return of the cage.

The rods 10 and 23 can be elongated or shortened by the use of turn buckles 28.

What is claimed is:

- 20 1. Caging apparatus including a cage shaft, a track leading thereto, bell crank levers arranged in pairs and having arms extending under the rails of the track and toward each other, horns carried by the 25 outer ends of the other arms of the bell crank levers, levers fulcrumed between the

rails of the track and engaging the inwardly extending arms of the bell crank levers of one pair, rods connecting said levers to the inwardly extending arms of the bell crank 30 levers of the other pair, a cross head connected to the rods, a spring engaging the cross head for exerting a constant pull thereon, a trip projecting into the shaft and adapted to be actuated by a cage, and 35 rod connections between the trip and the bell crank levers of one pair.

2. In caging apparatus the combination with a track, of a horn mounted to swing laterally relative to the track, and a brace 40 carried by the horn and movable to position onto a rail of the track to brace the horn when the horn is in wheel engaging position.

In testimony that I claim the foregoing 45 as my own, I have hereto affixed my signature in the presence of two witnesses.

ELMER EDMOND NIDA.
